UNITED STATES PATENT OFFICE

GEORGE W. OSBORNE, OF NORTH KANSAS CITY, MISSOURI

SALES-INDICATING MECHANISM

Application filed May 4, 1929. Serial No. 360,477.

My invention relates to improvements in sales indicating mechanisms.

One of the objects of my invention is to provide a novel indicating mechanism of the kind described, which, when a purchaser deposits a coin therein and manually actuates the mechanism, will render active a signalling device, which will continue active until an attendant operates the mechanism to reset

10 it in its initial condition.

A further object of my invention is the provision of novel coin actuated electrical switch mechanism arranged to be actuated by a purchaser so as to render active an electrical signalling device by closing the switch, the signalling device remaining active until an attendant opens the switch.

Still another object of my invention is novel means by which a register is actuated 20 simultaneously with the closing of the switch for registering the depositing of the coin in the apparatus.

A further object of my invention is to provide a novel indicating mechanism which is simple, cheap to make, durable, not likely to get out of order, which is easily operated and which is efficient in its operation.

The novel features of my invention are hereinafter fully described and claimed.

30 In the accompanying drawings, which illustrate the preferred embodiment of my invention,

Fig. 1 is a perspective view of an apparatus embodying my improved indicating mechanism.

Fig. 2 is an enlarged vertical sectional view, on the line 2—2 of Fig. 1, partly broken away, showing one of the switch and coin receiving boxes, with no coin therein, and with the switch in the open position.

Fig. 3 is a section on the line 3—3 of Fig. 6.

Fig. 4 is a view similar to Fig. 2, with the switch closed and a coin operatively engaging the switch operating member.

45 Fig. 5 is a section on the line 5—5 of Fig. 11, no coin being in the chute.

Fig. 6 is an enlarged view, partly broken away, partly in vertical section and partly in side elevation, of one of the switches shown in the closed position and parts con-

nected therewith, a coin operatively engaging the switch lever.

Fig. 7 is a fragmental view of some of the parts shown in Fig. 6, showing the switch lever in the open position and engaging a coin and the coin pushing member disengaged from the coin, a second coin being shown supported in the coin chute by the coin operated lever.

Fig. 8 is a view similar to Fig. 7, the switch lever being shown forced by the push member and a coin to the closed position, a second coin being shown supported in the chute by an arm carried by the switch lever.

Fig. 9 is a reduced top view of one of the boxes, the top being removed, and a portion of the box supporting table.

Fig. 10 is an enlarged section on the line 10—10 of Fig. 9, the switch being shown open.

Fig. 11, is an enlarged view taken on the plane of the line 11—11 of Fig. 10, showing partly in elevation and partly in vertical section part of one of the switch mechanisms and parts connected therewith, parts being broken away, and the switch lever shown in the open position.

Fig. 12 is a view similar to Fig. 7, showing the same parts as disposed in Fig. 7, the upper coin being omitted.

Fig. 13 is a reduced front elevation of the apparatus shown in Fig. 1.

Fig. 14 is a diagrammatic view of the electric circuit which includes the switches and signalling devices.

Similar reference characters designate similar parts in the different views.

1 designates a table top having a plurality of openings through which respectively extend the bodies 2 of boxes, the tops 3 of which rest on the top of the table top, each box top at one side of the body 2 having an observation opening 4 covered by a transparent glass plate 5.

The bottom of each box 2 has a lateral shelf extension 6. Said shelf extensions respectively support electrical signalling devices consisting of electric lamps 7, Fig. 13, which are respectively disposed so as to project light through the observation openings 4.

Below the horizontal plane of the shelves

6 is a coin receiving box 8, having at one end a closure 9 covering an opening in the end of the box through which coins therein may be removed.

5 Two inclined chutes 10 discharge into the box 8 at opposite sides thereof. Vertical coin chutes 11 have their upper ends extended respectively into the boxes 2, two of the chutes 11 discharging into one of the chutes 10 and the other two chutes 11 discharging into the other chute 10.

10 The table top 1 may be supported by any suitable means not shown.

15 The box tops 3 are respectively provided with coin receiving slots 12, and with observation slots 13 through which may be had readings of registers thereunder.

20 The box tops 3 are also respectively provided with slots 14 through which respectively extend manually operated levers 15, with which, after the deposit of coins in the slots 12, the purchasers operate a plurality of electrical switches and registers which are respectively contained in the boxes 2.

25 As the switches, coin actuated mechanisms and registers are all alike, a description of the mechanisms contained in one of the boxes 2 will suffice for each.

30 Each of the boxes 2 contains a vertical coin chute 16 which has its upper end communicating with the adjacent coin slot 12, and which at its lower end is provided with a seat 17, on which a coin A is adapted to rest, Figs. 7 and 12.

35 In each box 2 there is a switch mechanism having an oscillative operating member comprising, preferably, a lever having a downwardly extending arm 18, adapted when the switch is open to have the two fingers 19, with which it is provided at its lower end, Figs. 3, 7 and 12, disposed in front of and hold the coin A in the seat 17. Said switch lever is pivotally mounted on a horizontal pin 20 which is supported by two ears 21, which extend laterally from the chute 16, Figs. 2 and 3.

40 The switch lever is provided with a laterally extending arm 22 of insulating material fastened at one end to the arm 18, and carrying adjacent to its other end a conductive contact member 23, which is adapted, when the switch arm 22 is swung to the closed position, shown in Figs. 4 and 6, to be between and have electrical contact with two contact 45 springs 24 and 25, which are in circuit in series with one of the lamps 7, and which are disposed in circuit in multiple with the other spring contacts 24 and 25 of the other switches.

50 For normally forcing the switch arm 22 to the open position, shown in Fig. 11, said arm has attached to it one end of a coil spring 26, the other end of which is attached to a pin 27 mounted on a projection 28 extending from one side wall of the box 2.

55 For forcing the lever so as to swing the arm 22 to and in contact with the spring contacts 24 and 25 to close the switch, there is horizontally slideable in guides 29 on the coin chute 16, a manually operable push member 30, having a transverse pin 31 disposed in an end slot 32 in the lower end of the adjacent lever 15, which is pivoted on a horizontal axis in a post 33, which extends from the adjacent wall of the box 2.

60 A coil spring 34 has one end attached to the lever 15 below the post 33, the other end of the spring being fastened to a pin 35 mounted on the box 2. The spring 34 normally swings the lever 15 to the position shown in Figs. 2 and 11, thereby normally retracting the push member 30 to the position shown in Figs. 7, 11 and 12, in which position it is out of the path of a coin descending the chute 16 to the seat 17.

65 To hold the contact member 23 between and in contact with the spring contacts 24 and 25 against the pull of the spring 26, until an attendant releases the switch lever, as will be described, there is provided a detent comprising a member 36 pivotally mounted on the pin 27 mounted in the projection 28 on the wall of the box 2. A spring 39 coiled around the pin 27 has one end bearing against the wall of the box 2, and the other end bears against the detent 36, and normally forces it to the position shown in Fig. 6, in which position it engages the lower side of the arm 22 and holds the latter in the closed position. When the detent 36 is 70 swung to the position shown in Fig. 10, the spring 26 swings the arm 22 to the open position, shown in Figs. 10 and 11.

75 For simultaneously swinging the detents 36, which are holding the arms 22 of the switch levers in the different boxes 2 to the position shown in Fig. 10, in which the arms 22 are released from the detents 36 and rest respectively in notches 40 provided one in each detent 36, there is provided a horizontal releasing bar 41, Figs. 10 and 13, which extends transversely through holes provided therefor in the sides of the boxes 2, and is slid in one direction by means of a coil spring 42 attached at one end to one end of the bar 41 and at the other end to a pin 43 mounted on the left shelf extension 6, as viewed in Fig. 13.

80 The bar 41 has in it in each box 2 a longitudinal slot 44, Fig. 10, through which extends a pin 45 carried by the adjacent detent 36.

85 When the right end of the bar 41, as viewed in Figs. 10 and 13, is pulled by an attendant to the extreme right end of its movement, it will engage the pins 45 of such detents 36 as are in the switch arm holding position, shown in Fig. 4, and will swing the detents to the release position shown in Fig. 10, upon which the arm 22 will be swung downwardly by the spring 26 to the position shown in Fig. 10.

and in Fig. 11, in which position the arms 22 being in the notches 40 of the detents 36, thus holding the latter from being pulled by the springs 39 from swinging the detents to the 5 arm holding positions, shown in Figs. 4 and 6.

Respectively mounted in the boxes 2 are suitable registers 46, Figs. 2, 4 and 9, which are supported by the tops of the boxes 2, and are disposed so that their numbered wheels 47, Fig. 9, are visible through the observation slots 13. Each register has an oscillative operating lever 48, which is engaged by an arm 49 carried by the arm 18, which on each 15 oscillation of the arm 18 oscillates the lever 48, thus registering the coins inserted in the adjacent chute 16.

The contact springs 24 and 25 are fastened to opposite sides of an insulating block 50, which is fastened to the inner side wall of the 20 box 2 in which the particular switch is located.

For preventing a second coin B, which should happen to be inserted in a chute 16 when a coin A is resting on the seat 17, Fig. 7, there is pivoted between two ears 51 on the chute 16, on a horizontal pin 52, a lever having a downwardly extending arm 53 having an angular projection 54 which is normally held by gravity, when no coin is in the chute, in the path of a coin passing to the chute seat 17, as shown in Figs. 6 and 11.

The said coin actuated lever has an arm 55 which extends upwardly and which has a lateral extension 56, which is normally held out of the chute 16, but which, when a coin A is passing to the seat 17 and engages the projection 54, passes through a slot 57 in the chute 16, as shown in Fig. 12. When in this 40 position, the extension 56 of the arm 55 of the lever will engage and stop the downward movement of a coin B which may be inadvertently inserted in the slot, as shown in Fig. 7.

The push member 30 has a vertical end slot 45 58 through which the arm 53 of the coin actuated lever passes, so that the reciprocation of the push member 30 has no effect on the said lever, further than, when the push member 30 is forced against the coin A, Fig. 8, and causes 53 the coin A to force to the left the switch lever arm 22 to the switch closing position, Figs. 6 and 8, the coin actuated lever will swing by gravity from the position shown in Fig. 7 to the position shown in Fig. 8, in which latter position, the arm extension 56 will pass out of the chute passage, and the coin B will drop to the position shown in Fig. 8, in which position it rests on a coin supporting wire 58' fastened to the arm 49, which wire 58', when the switch lever is in the open position, Fig. 7, is out of the chute passage, but which, when the switch lever closes, enters the chute passage, through a slot 59, Fig. 8.

When the switch lever arm 22 is retracted 65 to the open position, Fig. 12, the wire 58' will

be withdrawn from the chute passage, thus permitting the coin B, which has rested thereon, to pass to the seat 17 to the position occupied by the coin A in Fig. 12.

As shown in Fig. 14, the spring contacts 24 are respectively connected by conductors 60 with a positive conductor 61 which is connected to one terminal of an electric generator 62, the other terminal of which is connected to a negative conductor 63. Conductors 64 70 respectively connect the contact springs 25 with one set of terminals of the electric signal lamps 7, the other terminals of which are respectively connected by conductors 65 to the negative conductor 63.

When the switch lever of any of the switches is closed and the contact member 23 of the switch is engaged with the spring contacts 24 and 25 of said switch, the current from the generator 62 will pass through the conductor 61, conductor 60 of the closed switch, spring contact 24, contact member 23, spring contact 25, adjacent conductor 64, adjacent lamp 7, adjacent conductor 65 and conductor 63 to the generator 62, thereby 80 lighting the lamp 7 of the set having the closed switch, and the light from said lighted lamp 7 will be projected through the observation opening 4 adjacent to said lamp, thus indicating to the attendant the chute 16 into 85 which a coin has been deposited.

When the attendant pulls the bar 41 to the clearing position at the extreme right, Figs. 10 and 13, the detents 36 will be operated to release the switch arms 22 which have been held closed, and the conductive members 23 which have been in contact with the adjacent contact springs 24 and 25 will be withdrawn therefrom, thereby opening the switches 90 which have been closed.

In the general operation of the apparatus, a purchaser inserts a coin through one of the slots 12. The coin passes into the adjacent chute 16 to the seat 17. The purchaser swings the adjacent lever 15 from the position shown in Figs. 1 and 2 to the position shown in Figs. 4, 6 and 8, thereby moving the adjacent push bar 30 so that it will engage the coin A that is resting against the fingers 19 of the lever arm 18 of the switch. The space between the fingers 19 is wide enough to permit the passage therebetween of the push member 30, so that if no coin is inserted and the lever 15 is operated, the switch will not be opened. The coin A, however, when on the seat 17 rests against the fingers 19, so that, when the push member 30 is moved to the position shown in Figs. 6 and 7, the switch lever will be swung to the closed position, in which position it will be held by the adjacent detent 36 engaging the arm 22 of the switch lever until the attendant pulls the clearing bar 41 to the position shown in dotted lines in Fig. 10.

When the attendant releases the bar 41, 130

the spring 42 will retract the bar 41, upon which the springs 49 will retract the detents 36 to their initial holding positions, Fig. 6, when the switch levers are again closed. When the attendant releases the bar 41, it will assume the position shown in solid lines in Fig. 10. When the purchaser releases the lever 15, the adjacent spring 34 will retract the lever 15 and the push member 30.

When the push member 30 is retracted, the coin A, which has been pushed from the seat 7 to the position shown in Fig. 6, being over the adjacent chute 11, will be released, as the adjacent detent will hold up the arm 22 in the closed position. The coin will drop into the chute 11 adjacent thereto, and thence in to the receiving box 8 through the adjacent chute 10.

With the mechanism hereinbefore described, the attendant is notified, by the lighting of the lamps, into which boxes purchasers have dropped coins, and the indication continues until the attendant pulls the clearing bar 41. The registers 46 show the number of coins which have been deposited in the several boxes.

I do not limit my invention to the structure shown and described, as many modifications, within the scope of the appended claims, may be made without departing from the spirit of my invention.

What I claim is:

1. In a sales indicating mechanism having a coin supporting seat and a manually operable push member for forcing a coin from said seat, the combination with an electrical signalling device, of a switch in circuit in series with said device and having an operating member out of the path of said push member and in the path of and arranged to be moved to the closed position by a coin as it is being forced from said seat by said push member, means for normally forcing said operating member to the open position, a detent arranged to engage and hold said operating member in the closed position and arranged to be held by the operating member, when the latter is in the open position, from moving to the holding position, means for normally forcing said detent to the holding position, and manually operated means for moving said detent from the holding position.

2. In a sales indicating mechanism having coin supporting seats and manually operable push members for respectively forcing coins from said seats, the combination with electrical signalling devices in circuit in multiple with each other, of switches respectively in circuit in series with said devices and provided respectively with operating members out of the paths respectively of said push members and respectively in the paths of and arranged to be respectively moved to the closed positions by coins forced from said

seats by said push members respectively, means for normally forcing said operating members to the open positions, detents arranged to respectively engage and hold said operating members in the closed positions, and respectively arranged to be held by said operating members, when the latter are in the open position, from moving to the holding positions, means for normally forcing said detents to the holding positions, and manually operated means for simultaneously engaging those detents which are in the holding positions and forcing them from the holding positions.

3. In a sales indicating mechanism having a coin supporting seat and a manually operable member for pushing a coin from said seat, the combination with an electrical signalling device, of a switch in circuit in series with said device and having an operating member out of the path of said push member and in the path of and arranged to be moved to the closed position by a coin as it is forced from said seat by said push member, means for normally forcing said operating member to the open position, a detent arranged to engage and hold said operating member in the closed position and arranged to be held by the operating member, when the latter is in the open position, from moving to the holding position, means for normally forcing said detent to the holding position, and a manually operated reciprocal member having a lost motion connection with said detent and arranged, when moved in one direction, to force said detent from the holding position.

4. In a sales indicating mechanism having a coin supporting seat and a manually operable member for pushing a coin from said seat, the combination with an electrical signalling device, of a switch in circuit in series with said device and having an operating lever out of the path of said push member and in the path of and arranged to be moved to the closed position by a coin as the coin is pushed from said seat by said push member, means for normally swinging said lever to the open position, a detent arranged to engage and hold said lever in the closed position and arranged to be held by said lever, when the latter is in the open position, from moving to the holding position, means for normally forcing said detent to the holding position, and a manually operable reciprocal member having a lost motion connection with said detent and arranged, when moved in one direction, to force said detent from the holding position.

5. In a sales indicating mechanism having coin supporting seats and manually operable push members for respectively forcing coins from said seats, the combination with electrical signalling devices in circuit in multiple with each other, of switches respec-

- tively in circuit in series with said switches and in multiple with each other and respectively provided with operating members out of the paths respectively of said push members and respectively in the paths of and arranged to be moved to the closed positions by coins forced from said seats by said push members, means for normally forcing said operating members to the open positions, oscillative detents arranged to respectively engage and hold said operating members in the closed positions and respectively arranged to be held by said operating members, when the latter are in the open positions, from moving to the holding positions, means for normally swinging said detents to the holding positions, and a reciprocative manually operated member arranged, when moved in one direction, to engage and simultaneously move said detents which are in the holding positions.
6. In a sales indicating mechanism having coin supporting seats and manually operable push members for forcing coins from said seats respectively, the combination with electrical signalling devices in circuit in multiple with each other, of switches respectively in circuit in series with said devices and in multiple with each other and respectively provided with operating members out of the paths respectively of said push members and respectively in the paths of and arranged to be respectively moved to the closed positions by coins forced from said seats by said push members, means for normally forcing said operating members to the open positions, detents for engaging and holding said operating members in the closed positions and provided each with a pin, means for normally forcing said detents to the holding positions, and a reciprocative bar having longitudinal slots receiving respectively said pins for forcing said detents from the holding positions.
- 45 7. In a sales indicating mechanism, a switch having an operating member adapted to be manually moved to the closed position, means for normally forcing said member to the open position, a signalling device in circuit in series with said switch, a detent, means for moving said detent normally to a position in which it will engage and hold said member in the closed position, and manually operated means engaging said detent for moving said detent from the holding position.
8. In a sales indicating mechanism, a switch having an oscillative operating member adapted to be manually swung to a closed position, means for normally swinging said member to the open position, an oscillative detent having a pin, means for normally forcing said detent to a position in which the detent will engage and hold said operating member in the closed position, a reciprocative member having a slot receiving said pin and

arranged to engage said pin so as to swing said detent from the holding position, and a signalling device in circuit in series with said switch.

9. In a sales indicating mechanism, having a coin chute provided with a coin supporting seat and having a manually operable push member for forcing coins from said seat, the combination with a switch having an operating member out of the path of said push member and in the path of coins forced by said push member from said seat, means for normally forcing said operating member to the open position, said operating member being adapted to be forced, by a coin forced from said seat by said push member, to the closed position, a stop member carried by said operating member and moved thereby into said chute so as to hold a coin from passing said chute to said seat when the operating member is in the closed position, and a second stop member having two arms one above the other the lower one of which is normally disposed in said chute and adapted to be engaged by a coin and moved to and held in a position thereby, when the coin is resting in said seat, such that the upper arm will extend into said chute and hold another coin passing through said chute to said seat, said second stop member being automatically movable, when no coin is in said chute to a position in which the lower arm will extend into the chute and the upper arm will be out of the path of coins passing through said chute.

In testimony whereof I have signed my name to this specification.

GEORGE W. OSBORNE.
